CLAIM

The ornamental design for a communication device, as shown and described.

DESCRIPTION

FIG. 1 is a front, right side, and top perspective view showing our new design for a communication device with broken line matter being for illustrative purposes only and forming no part of the claimed design.

FIG. 2 is a left side elevation view thereof with broken line matter being for illustrative purposes only and forming no part of the claimed design.

FIG. 3 is a top plan view thereof with broken line matter being for illustrative purposes only and forming no part of the claimed design.

FIG. 4 is a front elevation view thereof with broken line matter being for illustrative purposes only and forming no part of the claimed design.

FIG. 5 is a back elevation view thereof with broken line matter being for illustrative purposes only and forming no part of the claimed design.

FIG. 6 is a right side elevation view thereof with broken line matter being for illustrative purposes only and forming no part of the claimed design.

FIG. 7 is a bottom plan view thereof with broken line matter being for illustrative purposes only and forming no part of the claimed design; and,

FIG. 8 is a front, right side, and top perspective view of the communication device with dotted line subject matter removed.
